LIQUID HEATER

Frederick Edward Oldham, Mellor,
near Blackburn, EnglandApplication January 7, 1949, Serial No. 69,784
In Great Britain January 10, 1948

6 Claims. (Cl. 219—39)

1

This invention concerns water and other liquid heaters.

An object of the present invention is to provide a device which is particularly suitable for the heating of water in domestic water-heating systems including central heating systems. It is to be understood however, that the device is to be generally applicable to the heating of liquids.

It is intended by the provision of suitable means to ensure a flow of liquid from the lower to the upper part of the shell across the whole length of said shell, thus promoting substantially equal conditions in planes at right angles to the stream-lines. Efficiency and long life of the heating elements is also assisted since if this object is achieved flow is maintained past the whole length of the element ensuring that no part of said element is working at higher temperature than the rest.

According to the present invention a liquid heating device comprises a main shell or liquid heating chamber, one or more immersion heating elements of a suitable type, inlet or outlet orifices or both in the form of a narrow rectilinear slit of length substantially equal to that of the shell, and inlet and outlet pipes connected thereto by a header having a narrow rectilinear opening corresponding with the slit in the shell.

The immersion heating elements are preferably of the electrical resistance type.

Preferably the cross-sectional area of the outlet orifice is substantially equal to that of the outlet pipe, and the cross-sectional area of the inlet orifice to that of the inlet pipe, said orifices being axial of the shell.

The inlet and outlet pipes, which may be disposed centrally of their headers or at one end thereof, are preferably in the region of the lower and upper part of the shell respectively.

The invention will be described further by way of example with reference to the accompanying drawings, in which:

Fig. 1 is a front elevation of a preferred form of boiler; and

Fig. 2 is a sectional side elevation on the line 11—11 in Fig. 1.

A main shell or heating chamber which is of cylindrical form, is provided with headers 12, 13 and with supporting members 14 and 15. These parts may conveniently be of fabricated sheet metal construction with welded joints. An end plate 16 of the shell is bored with a convenient number of holes, in which are welded bushes 17, each having a flange 18 seating in the outside of end plate 16. Each bush 17 provides for the in-

2

sertion of an immersion heating element into the main shell heating chamber. The heating elements (not shown) are preferably provided with thermostatic control.

5 The main shell 11 has, at two diametrically opposite points on its periphery, axial inlet and outlet orifices formed by longitudinal slots 19 and 20 respectively. The region of the periphery of shell 11 in which slot 19 is formed is enclosed by the header 12 which is provided with an inlet pipe connection 21 at one end thereof constructed in a similar manner as the immersion heater entrance orifices, and of cross-sectional area substantially equal to that of slot 19. The region 10 of the periphery of shell 11 in which slot 20 is formed is enclosed by the header 13, which is provided with an outlet pipe connection 22 centrally disposed thereof of cross-sectional area substantially equal to that of slot 20. Each of 15 the headers has additional orifices therein whereby thermometers or thermostatic elements, for example, may be inserted. The header 12 may have such an orifice 23, while the header 13 may have orifices 24 and 25. Orifice 23 has 20 a thermostatic element, whilst 24 and 25 accommodate a safety-valve connection and a thermometer respectively.

In operation cool water enters by the inlet 21, through the header 12 and slot 19 and into the 25 shell 11. The water, heated by the means provided becomes less dense and is thereby assisted in its elevation to the upper part of shell 11 and then through slot 20 and header 13 and into the external heating system by way of the outlet 22.

30 I declare that what I claim is:

1. A liquid heating device comprising a liquid heating chamber, two headers for said liquid heating chamber, a liquid inlet flow pipe for one header, a liquid outlet flow pipe for the other header, a single liquid orifice between each respective header and the liquid heating chamber and liquid heating means in said liquid heating chamber, one of said liquid orifices being in the form of a rectangular slit of length substantially equal to the length of the liquid heating chamber, said rectangular slit being narrow in width as compared with the width of the said liquid heating chamber.

2. A liquid heating device as set forth in claim 1 in which each orifice is in the form of a narrow rectangular slit of length substantially equal to the length of the liquid heating chamber.

3. A liquid heating device as set forth in claim 55 2 in which the cross sectional area of each orifice

is substantially equal to the cross sectional area of its associated liquid flow pipe.

4. A liquid heating device as set forth in claim 1 in which the liquid heating means is constituted by a plurality of electrical resistance immersion heaters.

5. A liquid heating device as set forth in claim 4 in which the cross sectional area of each orifice is substantially equal to the cross sectional area of its associated liquid flow pipe.

6. A liquid heating device as set forth in claim 5 in which one header is at the bottom of the heating chamber and the other header at the top of the heating chamber, the first mentioned header having an inlet pipe therein, and the 15

second mentioned header having an outlet pipe therein.

FREDERICK EDWARD OLDHAM.
